TAPPER KEG VALVE

Carl C. Bauerlein, Clearwater, Fla., assignor to The Dole Valve Company, Morton Grove, Ill., a corporation of Illinois

Filed Dec. 14, 1962, Ser. No. 244,611

4 Claims. (Cl. 251—120)

This invention relates to a control valve and more particularly relates to an improved valve construction for use in dispensing beverages such as beer or carbonated drinks or the like and to a means of mounting the valve within a container.

In forming a valve designed to dispense fermented beverages such as beer, it is essential that the structure be of a smooth and continuous surface, entirely free from undercuts, crevices and pockets in which foreign bacteria can harbor and breed. Such bacteria would spoil the wort and result in disagreeable flavors and spoilage, and the most stringent methods of sterilization are necessary to maintain the integrity of the product. This requirement will dictate not only that the valve have smooth and continuous walls but that the materials of which it is composed be stable enough for repeated sterilization without being harmed.

This sterilization process is usually performed by back-flushing with a powerful detergent, under heat and pressure, and this stream must penetrate all areas of the structure in order to eliminate all pathogens. At the same time, the subsequent rinses must remove all of the detergent in order to preserve the flavor of the beer.

It has been found that the use of rubber as in seals, gaskets and diaphragms usually transfers off flavors when subjected to such treatment and an object of my invention is to provide a valve free from any flavor-imparting components.

It is a principal object of my invention to provide an improved fluid control valve designed primarily for use in dispensing beverages.

Another object of my invention resides in the provision of a valve of this character having flow restrictor means formed therein for retarding the flow of liquid as it passes through the valve to prevent undue foaming of the beverages as it is dispensed but with means for modulating the flow to provide a controlled amount of foam in the glass.

Yet another object of my invention is directed to the provision of a valve structure employing a minimum number of components at a cost which permits disposal after a determined number of usages.

Another object of my invention is to provide a simple, positive method of assembly to the container, sanitary and secure, without gaskets or screws or fasteners, yet which cannot readily be removed by rough handling or by unauthorized persons.

These and other objects and advantages of my invention will appear from time to time as the following specification proceeds and with reference to the accompanying drawings, wherein:

FIGURE 1 a vertical sectional view through a fluid control valve constructed in accordance with the principles of my invention and showing a container in broken lines with the valve properly mounted in it;

FIGURE 2 is a fragmentary sectional view through a portion of the above structure shown in FIGURE 1 in which a different form of diaphragm is employed from that shown in FIGURE 1; and

FIGURE 3 is a view taken along lines III—III of FIGURE 1 showing the interrelationship between the triangular guide and the valve inlet port.

A container 10 is shown in broken line in FIGURE 1. The container 10 has a recessed end wall 11 which has a

2

central aperture 12 formed therein and defined by an inwardly extending annular rim 13 formed integrally with the wall 11. A chamber 14 is formed within the container 10 and serves to contain a beverage to be dispensed.

5 The fluid control valve per se is indicated generally by the numeral 15 and comprises a housing having a chamber 16 formed therein and having a side wall 17 and opposed end walls 18 and 19. In the embodiment of my invention shown in FIGURE 1 the end wall 19 comprises a diaphragm which is molded integrally with the housing. An inlet passage 20 opens centrally through the end wall 18 to the chamber 16 and an outlet spigot 21 has an outlet passage 22 formed therein which also opens to the chamber 16. An intake tube 23 is shown 10 as being molded integrally with the housing and as being communicable with the intake passage 20. If desired, the intake tube 23 could also be formed as a separate member and fitted over a nipple defining the inlet passage 20.

15 In the embodiment of my invention shown in FIGURE 1 the housing is formed in two parts which are fitted together at 24. Heat can then be applied to the joint to provide a weld between the plastic body parts. Plastic is the material preferably used in making the valve structure inasmuch as this material is best suited to use in 20 making parts which must come in contact with foods or beverages.

25 The exterior of the housing has relatively large and small diameter portions 25 and 26 formed at the outlet and inlet ends, respectively, of the valve body. An annular skirt 27 extends rearwardly from the large diameter portion, which skirt tapers outwardly in a forward direction to define a shoulder 28. A flange 29 is also formed integrally with the housing and extends outwardly from 30 the housing at a point spaced forwardly of the shoulder 28 in a rearward direction. It can flex to exclude dirt by making tight contact with the container. The largest external diameter of the skirt 27 is slightly greater than the inner diameter of the annular rim 13.

35 The parts are arranged so that the valve body can be pushed into the center aperture 12 formed in the recessed end wall 11 until the skirt 27 is forced all the way through the aperture and into the position shown in FIGURE 1 with its shoulder 28 disposed in engagement 40 with the innermost portion of the inturned annular flange 13. When the valve is seated in the position shown in FIGURE 1 the flange 29 is placed under a slight compression load so as to maintain the valve in the position shown in FIGURE 1.

45 As above noted, the valve body is formed of a plastic material and the diaphragm which acts to form the end wall 19 is molded integrally with the housing.

50 The diaphragm has an outwardly extending raised bead 55 formed therearound and has a valve rod 31 formed integrally therewith and centrally thereof having an elongated portion 32 extending into the interior of the chamber 16 for axial movement therein and having a head 33 extending exteriorly of the diaphragm. A shoulder 34 is formed at an angle of about 45° with respect to the center axis of the valve rod 31 intermediate the large and small diameter portions 35 and 36, respectively, of the chamber 16. The shoulder 34 acts as a seat for a valve member 37 which is connected to and operated by the valve rod 31. The valve member 37 has a face which 60 is complementary to the seat 34 and which is cooperable with that seat to control the flow of liquid from the inlet passage 20 to the outlet passage 22. The valve member 37 also has a guide 38 extending rearwardly thereof which is triangularly shaped in cross section as may be seen 65 in FIGURE 3 and which may be considered as an extension of the valve rod 31. The guide 38 extends into the inlet passage 20 and acts as a rearward guide for the 70

valve rod 31. Since the guide 38 has a triangular configuration liquid can freely pass around it from the inlet passage to the chamber 16.

The valve member 37 has a flow restrictor boss 39 formed integrally therewith which is seated in close fitting coaction with the small diameter portion of the chamber 16. A spiral form groove 40 is cut within the side wall of the boss 39 to define a spiral form passage between the boss 39 and the wall of the housing.

Consequently, when the valve rod 31 is in the position shown in FIGURE 1, liquid can freely pass from the inlet end of the chamber 16 between the inclined seat 34 and the complementary face of the valve member 37 and thence through the spiral form passage formed between the boss 39 and the housing wall to the outlet end of the chamber 16 and then through the outlet passage 22. Upon movement of the valve rod 31 to the right as shown in FIGURE 1 the face of the valve member 37 will contact the inclined seat 34 and liquid flow through the valve will cease.

A handle 41 is employed to effect axial movement of the valve rod 31. The handle 41 is pivotally mounted about a pin 42 and has a finger 43 which has its free end positioned in engagement with a stop block 44 formed integrally with the housing. An intermediate section of the finger 43 extends over and engages the outwardly extending portion 33 of the valve rod 31. In addition, an arm 45 extends rearwardly from the main body of the handle 41 and is movable into engagement with a portion 48 of the housing or a pin 47 extending from the housing as the handle 41 pivots in one direction or another. The handle 41 is also formed of a resilient plastic material so that when the handle is pulled in a clockwise direction to the position viewed in FIGURE 1 the intermediate portion of the finger 43 will move sufficiently to the left to depress the valve rod 31 and unseat the valve member 37 from the seat 34. When the handle 41 is released the resiliency of the finger 43 will act to return the handle 41 to a normal position in which the arm 45 is in engagement with the portion 48 of the housing. It is important to understand that in the position shown in FIGURE 1 the finger 43 is in a stressed condition and that the outer free end of this finger will remain in engagement with the block 44 even though the handle 41 is pivoted in a counterclockwise direction.

The embodiment of my invention illustrated in FIGURE 2 differs from that shown in FIGURE 1 only in that a diaphragm 50 is provided which is separate from the housing 51. As with the structure shown in FIGURE 1 however, the valve rod 31 is formed integrally with the diaphragm 50. Also, the diaphragm 50 may be formed of the same or a different material as the housing 51 and is preferably formed of a resilient plastic material which is suitable for use in parts which come in contact with foodstuffs. In this embodiment of the invention the thin walled diaphragm 50 has a relatively thick walled substantially rectangularly configurated annular bead 52 formed about the periphery thereof. The bead 52 has an outer side wall 53 which tapers inwardly from the inner to the outer surface of the bead. An undercut annular groove 54 is formed within the housing 51 about the chamber 16 and is complementary in configuration to the bead 52 so that the bead can be snapped into the position shown in FIGURE 2 to securely lock the diaphragm 50 in its proper position in the housing 51. This method of securing the diaphragm to the housing offers the greatest simplicity insofar as manufacture and assembly is concerned and yet forms a clean inner surface for the chamber 16 and diaphragm 50 so that no grooves or sharp corners or the like are provided which might act to entrap small foreign particles.

It will be understood that these embodiments of my invention have been used for illustrative purposes only and that various modifications and variations in my in-

vention may be effected without departing from the spirit and scope of the novel concepts thereof.

I claim as my invention:

1. A fluid control valve comprising a housing having a chamber formed therein and having side and end walls defining said chamber,

an inlet passage opening through one of said walls of said housing to said chamber,

a flexible diaphragm forming one end wall of said housing,

an outlet opening through said side wall of said housing to said chamber,

a valve rod connected to said diaphragm and extending into and guided by said inlet passage,

a valve seat formed within said chamber between said inlet passage and said outlet and facing in the direction of said inlet passage,

a valve member connected to said rod and movable therewith and cooperable with said seat to control the flow of fluid through said valve,

flow restrictor means for retarding the flow of fluid from said inlet passage toward said outlet once said valve is in an unseated position,

a handle pivotally mounted on said housing having a resilient finger formed integrally therewith, said resilient finger having an outer free end engageable with a portion of said housing,

wherein a central portion of said finger overlies and is engageable with the outer free end of said rod so that pivotal movement of said handle in one direction will bow said finger to effect a movement of said rod.

2. A fluid control valve comprising a housing having a chamber formed therein and having side and end walls defining said chamber,

an inlet opening through one of said walls of said housing to said chamber,

a flexible diaphragm forming one end wall of said housing,

an outlet opening through said side wall of said housing to said chamber,

a valve rod connected to said diaphragm and extending into said chamber,

a valve seat formed within said chamber between said inlet and said outlet,

a valve member connected to said rod and movable therewith and cooperable with said seat to control the flow of fluid through said valve,

flow restrictor means for retarding the flow of fluid from said inlet passage toward said outlet once said valve is in an unseated position,

and a handle pivotally mounted on said housing having a resilient finger formed integrally therewith, said resilient finger having an outer free end engageable with a portion of said housing,

wherein a central portion of said finger overlies and is engageable with the outer free end of said rod so that pivotal movement of said handle in one direction will bow said finger to effect movement of said rod.

3. A fluid control valve comprising a housing having a chamber formed therein and having side and end walls defining said chamber,

an inlet opening through one of said walls of said housing to said chamber,

an outlet opening through said side wall of said housing to said chamber,

a valve rod extending through one of said end walls of said housing and extending into said chamber,

means guiding said rod for axial movement within said chamber,

a valve seat formed within said chamber between said inlet and said outlet,

a valve member connected to said rod and movable therewith and cooperable with said seat to control the flow of fluid through said valve,

- a flow restrictor boss on said valve member having a side wall having close fitting coaction with a side wall of said housing defining said chamber irrespective of the position of said valve member relative to said seat, 5
- a spiral form groove cut in the side wall of said boss and acting in cooperation with the side wall of said housing defining said chamber to define a spiral form passage to conduct liquid from said inlet to said outlet when said valve is in an unseated position, 10 and a handle pivotally mounted on said housing and having a resilient finger formed integrally therewith, said resilient finger having an outer free end engageable with a portion of said housing, 15 wherein a central portion of said finger overlies and is engageable with the outer free end of said rod so that pivotal movement of said handle in one direction will bow said finger to effect movement of said rod.
4. A fluid control valve comprising a valve body having a chamber formed therein and having side and end walls defining said chamber, 20 inlet and outlet passages opening through walls of said housing to said chamber, a port communicating said inlet and outlet passages, a valve seat defining said port, a valve member cooperable with said port to control the flow of fluid therethrough, a valve member operator connected to said valve member and extending through one of said housing walls,

15

10

15

20

25

a lever member pivotally mounted on said valve body, said pivotally mounted lever member contacting said valve body in both a clockwise and a counterclockwise rotational sense, thereby limiting pivotal movement of said lever to deflections caused by stresses within the lever material itself, said lever having a handle portion of substantially rigid material and a finger portion of substantially resilient material, and a pivot point intermediate said handle and lever portions, said finger portion being stressed about the outer free end of said valve member operator and having a finger tip terminating in contact with said valve body, thereby preventing pivotal movement of said finger tip.
